UNITED STATES PATENT OFFICE

112,690

DESIGN FOR AN ASHTRAY

Ray A. Bruner and Carl A. Mitchell, Muncie, Ind.

Application September 23, 1938, Serial No. 80,060

Term of patent 7 years

To all whom it may concern:

Be it known that we, Ray A. Bruner and Carl A. Mitchell, both citizens of the United States of America and residents of Muncie, county of Delaware, State of Indiana, have invented a new, original, and ornamental Design for an Ashtray, of which the following is a specification, reference being had to the accompanying drawing, forming part thereof.

The figure is a perspective view of an ashtray showing our new design.

We claim:

The ornamental design for an ashtray, substantially as shown.

RAY A. BRUNER.
CARL A. MITCHELL.
